GARMENT HANGER

Arthur E. Kammritz, East Hartford, Conn.

Application September 16, 1931, Serial No. 563,116

5 Claims. (Cl. 223—64)

My invention relates to the class of devices which are used for hanging articles of clothing, more especially coats and dresses, and particularly the latter, and an object of my invention, among others, is to provide a garment hanger in which garments of light sheer material may be retained on the hanger and in their original form.

One form of a hanger embodying my invention and in the construction and use of which the objects herein set out, as well as others, may be attained as illustrated in the accompanying drawing, in which—

Figure 1 is a front view of my improved garment hanger showing in dotted lines the retainers in their released positions.

Figure 2 is a top view of the same.

Garment hangers at the present time are frequently made of a thin strip of material curved as to its upper edge to conform somewhat to the shape of the shoulders of the garment, and such hangers, especially when used for hanging ladies' dresses or similar articles of thin sheer material are very smooth in order to avoid injury to the garments, and unless some means are provided for retaining the garments in place they very readily slip off the ends of the hangers. It is to obviate this condition and to provide means that may be readily manipulated for holding a garment in place upon a hanger that my present invention has been made.

In the accompanying drawing the numeral 5 denotes the support of the hanger that is made from a strip of wood or other suitable material and that may be smoothly finished to avoid injury to garments placed thereon. A hook 6 is secured to the support and extends from its upper edge midway between the ends, this hook being of any form common to devices of this class.

Retainers are pivotally attached to the support on opposite sides of the hook, in the particular form shown herein, each retainer comprising two branches 7—8 adapted to be located on opposite sides of the support 5 and joined at the outer end of the retainer by a bend 9 that is adapted to lie against the edge of the support to hold a garment in place.

These retainers are preferably formed from spring wire and of a material that will not tarnish or rust. They are also provided with inherent spring qualities which enable them to be retained in their closed positions and also in their opened or releasing condition. In order to attain this result one of the branches as 8, is

made shorter than the other branch, as 1, and these branches are formed at their ends with pivots 10—11 bent at substantially right angles to the branch from which it projects. Holes 12—13 are formed through the support 5 to conform to the lengths of the branches.

As a retainer is swung on its pivots the arm of the lesser length traveling on a shorter radius causes a distortion of both arms which results in creating a spring action in the arms, and this spring action will force the arms to opposite sides of a center line passing through the pivots and at the joined ends of the arms.

In order to serve my purpose I so locate the holes 12—13 that the spring action hereinbefore referred to will force the retainer toward the support from a point somewhat removed from the edge of the support, that is, the center line through the pivots 12—13 will be located at a short distance from the upper edge of said support, it being understood that the description relating to one of the retainers applies equally to both. This action of the retainer is illustrated in Figure 1 in which the open position of the retainer is shown in dotted outline. As a retainer is swung toward the support from this position a tension is placed upon the branches, this tension being greatest at that point where the outer end of the retainer reaches the line extending through the pivots 12—13.

As the end of the retainer passes this point which is designated as a, the reaction of the spring forces the retainer toward and against the edge of the support 5. In releasing the retainer the opposite action takes place and when the end of the retainer passes the point a the spring reaction forces the retainer into the opposite site position shown in dotted lines.

It will be seen from this construction that I have provided a garment hanger comprising retainers that will be automatically forced into their closed positions to retain a garment in place, and also the retainers will be automatically forced into their open positions and retained in such positions so that a garment may be readily placed upon the support, and while held by the fingers of the hands the thumbs may be employed to move the retainers to a point where they will snap into position to retain the garment in place. It will be noted that by locating the pivot holes 12—13 so that the point a is at some distance from the edge of the support 5, the force of the spring is lessened as the retainer moves from the point a toward the support, with a result that the pressure of the retainer against a garment is lessened and is

sufficient merely to retain the garment in place, and there is therefore no danger of injury to the garment by excessive spring pressure thereon.

I claim:

- 5 1. A garment hanger including a support to receive a garment, a retainer, means for movably attaching said retainer to said support, and means wholly inherent in said retainer and its attaching means for moving the retainer from a certain 10 point toward the support to hold a garment in place and for moving said retainer from said point away from said support to maintain said retainer in either of its extreme positions.
- 15 2. A garment hanger including a support to receive a garment, a retainer constructed of resilient material, means for pivotally attaching said retainer to the support, and means wholly inherent in said retainer and its attaching means and effective by spring qualities of the retainer 20 for swinging it from a certain point toward the support to hold a garment in place, and from said point away from said support, and to maintain said retainer in either of its extreme positions.
- 25 3. A garment hanger including a support to re-

ceive a garment, a retainer comprising two arms of unequal lengths and of resilient material, means for separately pivotally attaching each of said arms to said support, and means to effect through spring action of said arms, by reason of their unequal lengths, a pressure on the retainer against the support.

4. A garment hanger including a support to receive a garment, a retainer pivotally attached to the support and comprising two arms of unequal lengths, said support having pivot openings for the ends of said arms, said openings being relatively positioned to cause a resultant spring action of said arms to force them both toward and away from the support.

5. A garment hanger including a support to receive a garment, a retainer pivotally attached to the support each retainer comprising a piece of wire bent into U-shape with arms of unequal lengths, the ends of the arms being bent to form pivots, and the support having holes to receive said pivots, said holes being relatively positioned to force the retainers through action of the arms both toward and away from the support.

ARTHUR E. KAMMRITZ.
